(57) CLAIM

The ornamental design for a memorial, as shown and described.

DESCRIPTION

FIG. 1 is a front perspective view of memorial showing my new and original design;

FIG. 2 is a front elevation view thereof;

FIG. 3 is a back elevation view thereof;

FIG. 4 is a right side elevation view thereof;

FIG. 5 is a left side elevation view thereof; and,

FIG. 6 is a top view thereof.

The view of the bottom side of the memorial has been omitted because such side is flat and devoid of surface ornamentation. The broken lines form no part of the claimed design.
